LIP TURNING MACHINE

Charles G. Brostrom, South Peabody, Mass., assignor to United Shoe Machinery Corporation, Paterson, N. J., a corporation of New Jersey

Application August 10, 1935, Serial No. 35,657

14 Claims.

(Cl. 12—30)

This invention relates to lip turning machines and is herein illustrated and described as embodied in a machine for raising and setting the lip of an outsole which may be temporarily attached to a shoe.

It is an object of the invention to provide an improved machine of the type under consideration. In accordance with a feature of the invention a pair of members are provided which are reciprocated alternately in substantially parallel paths, one of the members being constructed and arranged to raise a channel lip and the other to turn back the lip after it has been raised. In the illustrated construction, the two members for operating upon the lip are arranged in side-by-side relation to each other for reciprocation transversely or widthwise of the channel. As illustrated herein, the member which operates to turn back and set the lip has an under surface which is adapted to ride over the raised lip. This lip-turning member is mounted for yielding movement upwardly from the channel and is urged downwardly by a spring to cause it to exert downward pressure upon the lip. The illustrated construction includes also a gage in the form of a blade-like member adapted to enter the channel, which gage is vibrated in a direction lengthwise of the channel to facilitate the feeding of the sole. As seen in outline, the leading edge at the outer end of the illustrated gage is gently rounded, while the trailing edge recedes more abruptly to enable the gage to exert a pawl-like feeding action upon the sole. In the illustrated machine the tools for raising and setting the lip are mounted, respectively, upon bars which are connected by a system of levers to constrain the movements of the bars substantially to reciprocation in opposite directions and in parallel paths, means being provided for reciprocating one of the bars to operate the tool supported by that bar and to operate also, through the system of levers, the tool supported by the other bar.

The invention further consists in features of construction and combinations and arrangements of parts hereinafter described and claimed.

The invention will be explained with reference to the accompanying drawings, in which

Fig. 1 is a view in side elevation of the improved machine;

Fig. 2 is a plan view of the machine shown in Fig. 1;

Fig. 3 is a sectional view taken on the line III—III of Fig. 2 looking in the direction of the arrows;

Fig. 4 is a perspective view of the members which operate upon the sole;

Figs. 5 and 6 are plan views showing the elements illustrated in Fig. 4 in different positions of operation upon a sole;

Fig. 7 is a sectional view taken on the line VII—VII of Fig. 2;

Fig. 8 is a sectional view taken on the line VIII—VIII of Fig. 6;

Fig. 9 is a perspective view in inverted position of one of the members shown in Fig. 4.

The operating members of the improved machine comprise a pair of tools 10 and 12 which, as shown in Figs. 4, 5, and 6, are arranged in side-by-side relation to each other. The tools 10 and 12 are reciprocated alternately by the mechanism which will later be described. Figs. 5 and 6 show these tools in operation upon a sole S upon which is formed a channel lip L. The tool 10 has an end portion 14 adapted to raise the lip L, the end portion 14 being concave in a direction heightwise of the sole and convex in a direction lengthwise of the sole. The tool 12 has an under surface 16 which, as shown in Fig. 1, inclines upwardly at an angle of about 8° toward the outer end of the tool. The inner or lower end of the inclined surface 16 is concave as shown in Fig. 8 to avoid creasing the lip L sharply at the shoulder. The tool 12 has an extension 18 which increases the bearing area of the under surface 16. A shallow groove 15 of rounded cross section extends across the surface 16 in a direction which is lengthwise with respect to the lip L, the groove 15 constituting a local increase in the concavity of the surface 16. Extending downwardly from the inner portion of the surface 16 is a rounded nose 17 having an under bearing surface 19. Beneath the tools 10 and 12 is a thin blade-like gage 20 adapted to enter the channel and to engage the root of the channel lip L, otherwise known as the shoulder of the channel to position the sole in proper relation to the tools 10 and 12. As shown in Figs. 5 and 6, the gage 20, as seen in outline, has the outer end of its leading edge gently rounded, as indicated by the reference character 22 on Fig. 5, while the outer portion of its trailing edge recedes more abruptly, as indicated by the reference character 24. The gage 20 is not stationary but, as will later be explained, oscillates in a manner to impart a feeding movement to the work. As the tools 10 and 12 are reciprocated the tool 10 will first engage the channel lip to raise it in upstanding position; the tool 16 will

then advance into engagement with the raised lip and turn it back to set the lip.

The entire machine will now be described. The supporting structure of the machine comprises a frame 26 adapted to rest upon the floor and having a heightwise adjustable column 28 which carries a head 30. The head 30 is in the form of a housing adapted to contain a liquid lubricant and is provided with a cover plate 32 (shown only in Fig. 1). Lubricant may be introduced into the housing 30 through a filler 34. Mounted upon a lower portion of the frame 26 is a motor 36 upon the shaft of which is mounted a driving pulley 38. Journaled in bearings 40 in the housing 30 is a shaft 42 upon which is secured a pulley 44. The shaft 42 is driven by a belt 46 which passes over the pulleys 38 and 44. A disk 47 is secured upon the shaft 42 for raising a spray of lubricant within the housing 30. Mounted upon the shaft 42 by a ball bearing as shown in Fig. 3 is an eccentric 48 from which extends an arm 50. The arm 50 is connected to a mechanism which will now be described for operating the tools 10 and 12 and the gage 20.

Secured within the housing 30 is an upstanding bearing pin 52 (Figs. 1, 2, and 7) upon which is mounted a lever 54. The central portion of the lever 54 is provided with a downwardly extending boss 56 which rests upon an upwardly extending boss 58 formed on the bottom wall of the housing 30. The lever 54 has an arm in the form of a pair of spaced ears 60 (Fig. 7) and a similar arm extending in the opposite direction in the form of spaced ears 62. The lever 54 is further provided with a third arm 64 (Fig. 2) extending centrally from the lever and at right angles to the arms above described. A second bearing pin 66 (Fig. 1) extends upwardly within the housing 30 and carries a lever 68 which is similar in all respects to the above-described lever 54 except that in the lever 68 the third arm 64 is omitted. A bar 70 extending between the ears 60 is pivotally connected to the lever 54 by a pin 12. The bar 70 extends through corresponding ears in the lever 68 and is pivotally connected to that lever by a pin 74. A bar 76 extends between the ears 62 of the lever 54 and is pivotally connected to that lever by a pin 78. The bar 76 extends between corresponding ears in the lever 68 and is pivotally connected to that lever by a pin 80. As shown in Fig. 2, the bars 70 and 76 are in substantially parallel relation to each other, and the levers 54 and 68 are in substantially parallel relation to each other. By reason of this arrangement the bars 70 and 76 will be constrained to move in opposite directions. The fulcrum bearings of the above-mentioned levers are lubricated by a wick 82 which dips down into the lubricant contained within the housing. Other wicks 84 (Figs. 1 and 7) are provided for the pivotal connections of the bars to the levers. The bar 70 has a rearward extension 86 terminating in a sleeve which surrounds a pin 88 carried between a pair of ears 90 extending from the arm 50. Oscillatory movement is transmitted from the eccentric 48 through the arm 50 to the pin 88, and thence to the extension 86 of the bar 70; and from the bar 70 through the levers 54 and 68 to the bar 76. The bars 70 and 76 are thus reciprocated alternately in opposite directions. The bars 70

and 76 extend outwardly through suitable openings in a felt partition 92 for preventing the escape of splashed lubricant, and thence out through an opening in an extension 93 of the housing 30.

The tool 10 is rigidly secured to the outer end of the bar 70 by a pair of screws 94. The tool 12 is pivotally mounted for heightwise movement upon a pin 96 which is secured in the forked end of a block 98, the rear portion of the block 10 being rigidly secured by screws 100 to the outer end of the bar 76. A recess 101 is formed in the adjacent face of the tool 10 to accommodate the end of the pin 96 and a nut which secures the pin, as shown in Fig. 5. A double-leaf spring 102 which is secured by screws 104 to the block 98 bears against the upper surface of the tool 12 to urge the tool downwardly.

The reciprocatory movement of the bars 70 and 76 is thus transmitted to the tools 10 and 12. The tools 10 and 12 are positioned so as to be substantially in sliding engagement with each other. Their reciprocatory movement, however, will have a transverse component owing to the fact that the bars 70 and 76 are mounted upon levers. This transverse component, although slight, is of material assistance in the feed of the work, its effectiveness being due in part to the rapid speed at which the tools are driven. No special provision is necessary for the transverse component of the bar 70 in its connection to the arm 50, the transverse component being so slight as to be taken up between the terminal sleeve on the extension 86 and the pin 88.

The gage 20 is mounted for horizontal pivotal movement upon a vertical pin 106 which is secured in a block 108 having provision for adjustment in a direction parallel to the path of reciprocation of the tools 10 and 12. To this end the block 108 is slidably mounted in a guideway 110. A clamping screw 112 is provided for securing the block 108 in adjusted position. The guideway 110 is secured by a clamping screw 114 to a vertical wall 115 of the housing 30, a depending flange 117 of the guideway 110 being suitably guided for vertical adjustment relatively to the wall 115 and having a vertical slot to accommodate the screw 114. The heightwise adjustment of the gage 20 should be such as to bring it into sliding engagement with the under surface of the working end portion of the tool 10 which is extended downwardly, as indicated by the reference character 119, to provide a bearing surface of limited area at the end portion of the tool 10. The gage 20 functions also as a stop for the tool 12 under the pressure of the spring 102, the bearing surface 19 being in sliding engagement with the gage 20. The gage 20 has a tail portion 116 extending rearwardly of the pivot 106. Pivotally mounted upon the tail 116 is a block 118 which is received within a slot formed in the lever arm 64. It is apparent that the oscillatory movement of the lever 54 will be transmitted through the block 118 to the gage 20, causing the gage 20 to oscillate or vibrate in the line of feed of the work.

In the operation of the machine a shoe, to which is temporarily attached a channeled sole S, is presented by hand to the operating tools. The lip L is turned over by hand at a locality 70 adjacent to one end of the channel and the shoe is presented with the tool 12 extending over the turned-over portion of the lip and with the gage 20 extending into the channel. The operator presses the shoe upwardly and toward the right, 75

as viewed in Fig. 8, against the gage 20, with the root of the lip L in contact with the end of the gage. As the tools 10 and 12 reciprocate alternately the tool 10 and the nose 19 will deliver a series of rapid blows against the lip L. The tool 10, as already described, will progressively raise the lip L to or slightly beyond upstanding position, while the under surface 16 of the tool 12 will progressively ride over the turned-up lip and 10 turn back and set the lip. The sole S is provided with the usual channel groove G for receiving the stitches which unite the sole to the upper. When the channel lip L is turned back it tends to overhang the groove G, and would 15 interfere with the subsequent stitching operation if set in this position. The purpose of the nose 19 on the underside of the tool 12 is to push the root of the partially turned lip clear of the groove G. It can best accomplish this purpose if permitted, on its outward stroke, to travel slightly beyond the end of the gage 20; and the gage 20 is accordingly adjusted, through the block 108 and clamping screw 112, in such relation to the 20 stroke of the tool 12. This action of the nose 19 upon the lip L is illustrated in Fig. 8. The nose 19 is rounded to facilitate feeding the more sharply curved portions of the sole, as at the ball line and toe. The groove 15 accommodates the natural curvature of the turned-over lip, 30 and avoids deforming the lip by pressing it flat.

The gage 20 not only positions the sole in proper relation to the tools 10 and 12 but also, by reason of its oscillation, imparts a feeding movement to the shoe to feed the channel lip 35 past the tools 10 and 12. This feeding movement results from the fact that the operator presses the shoe to the right, as viewed in Fig. 8, with the shoulder of the channel in frictional engagement with the end of the gage 20. The gage 20, 40 each time it advances in the direction of feed, thus carries the work along with it. During each back-feed movement of the gage 20, however, the tool 10 is exerting an outward thrust against the lip L which overcomes or relieves the pressure of 45 the shoulder of the channel against the end of the gage 20, thereby minimizing any tendency of the gage to impart a back-feed movement to the work. The blow of the nose 19 against the lip L does not occur until the feed stroke of the 50 gage 20 has been substantially completed, and does not therefore interfere with the feeding action of the gage. The movement of the gage, which is rapid enough to amount to vibration, reduces the frictional resistance of the flat under 55 surface of the gage against the channel base. The shape of the gage, with the leading edge gently rounded at 22 and the trailing edge receding abruptly at 24, enables it to exert also a pawl-like feeding action upon the work.

60 Figs. 5 and 6 show the operating instrumentalities of the machine in opposite phases. In Fig. 5 the tool 10 is shown as fully retracted, the tool 12 as fully advanced, and the gage 20 as at the end of its feeding stroke. In Fig. 6 the tool 10 is shown 65 as fully advanced, the tool 12 as fully retracted, and the gage 20 as at the beginning of its feeding stroke. A speed of 6100 revolutions per minute of the shaft 42 has been found most satisfactory.

70 As shown in Figs. 5 and 6, the lip L, while directly under the tool 12, is turned over almost 180° upon the surface of the sole. It is not always desirable to set the lip in this position and consequently, in the illustrated machine, the shape 75 and inclination of the under surface of the tool

12 and also the pressure of the spring 102 are arranged to impart a set to the lip which will permit the lip to return to substantially upright position and remain in that position. The feeding action of the gage 20 is sufficient to advance the sole with little effort on the part of the operator, whose principal task is to hold the shoe with the sole in proper relation to the gage 20.

Having thus described my invention, what I claim as new and desire to secure by Letters Patent of the United States is:

1. A channel opening machine having a tool for raising a channel lip from a sole, means for reciprocating said tool, a tool for turning back the raised lip, and means for reciprocating the lip-turning tool in a path extending substantially widthwise of the channel.

2. A channel opening machine comprising a pair of reciprocatory tools constructed and arranged to raise a channel lip on a sole and to turn back the lip respectively, and means for reciprocating said tools alternately in substantially parallel paths.

3. A channel opening machine comprising a reciprocatory tool constructed and arranged to raise a channel lip formed on a sole, a reciprocatory tool arranged in side-by-side relation to the first-mentioned tool and having an undersurface adapted to ride over the raised lip to turn back and set the lip, and means for reciprocating said tools alternately in paths which are substantially widthwise with respect to the channel.

4. A channel lip setting tool having a surface adapted to bear upon a channel lip to set the lip, said surface having a groove formed in it to accommodate the lip and thereby to avoid flattening the lip, and said tool having a nose extending beyond said under surface for pushing the base of the channel lip clear of the stitch-receiving groove of the sole upon which the lip has been formed.

5. A channel opening machine comprising a blade-like member adapted to enter a channel formed in a sole, means for vibrating said blade-like member lengthwise of the channel to facilitate feeding of the sole, and means acting progressively upon the flap of the channel as the sole is being fed to open the channel flap.

6. A channel opening machine comprising a blade-like gage adapted to enter a channel formed in a sole and to engage the base of the channel flap, means for vibrating said gage lengthwise of the channel to facilitate feeding of the sole, the leading edge of said gage being smoothly rounded and the trailing edge receding abruptly to enable said gage, as it is vibrated, to act as a pawl in feeding the sole, and means acting progressively upon the flap to open the flap as the sole is fed.

7. A channel opening machine comprising a pair of reciprocatory members in side-by-side relation constructed and arranged to raise a channel lip on a sole and to turn back the lip respectively, a thin blade-like gage adapted to enter the channel of the sole, and means for vibrating said gage in a direction transverse to the direction of reciprocation of said tools to facilitate feeding of the sole.

8. A channel opening machine comprising a pair of tools constructed and arranged respectively to raise a channel lip on a sole and to set the lip, a pair of bars for supporting said tools respectively, connections between said bars constructed and arranged to constrain the movements of said bars substantially to reciprocation

in opposite directions and in parallel paths, and means for reciprocating one of said bars to operate the tool supported by that bar and to operate also, through said connections, the tool supported by the other bar.

9. A channel opening machine comprising a pair of tools constructed and arranged respectively to raise a channel lip on a sole and to set the lip, a pair of substantially parallel bars for supporting said tools respectively, a pair of parallel levers each pivotally connected to both of said bars, a pivotal support for each of said levers, and means for reciprocating one of said bars to operate the tool supported by that bar and to operate also, through said levers, the tool supported by the other bar.

10. A channel opening machine comprising a pair of tools constructed and arranged respectively to raise a channel lip on a sole and to set the lip, a pair of substantially parallel bars for supporting said tools respectively, a thin blade-like gage adapted to enter the channel of the sole, a support for said gage, a pair of parallel levers each pivotally connected to both of said bars, a pivotal support for each of said levers, means for reciprocating one of said bars to operate the tool supported by that bar and to operate also, through said levers, the tool supported by the other bar, and a connection between one of said levers and said gage constructed and arranged to transmit oscillatory movement to said gage to facilitate feeding of the sole.

11. A channel opening machine comprising a pair of tools constructed and arranged respectively to raise a channel lip on a sole and to set the lip, a pair of substantially parallel bars for supporting said tools respectively, a pair of levers for supporting and guiding said bars, each of said levers having one of its ends pivotally connected to one of the bars and its other end pivotally connected to the other bar, a pivotal support for each of said levers, said pivotal supports being positioned between said bars and spaced from each other lengthwise of the bars, and means for oscillating said bars and levers to cause said bars, by reason of their connections to said levers, to reciprocate alternately with respect to each other.

12. In a machine of the class described, a feed member against which the work piece is held by hand, means for oscillating said feed member, an operating tool constructed and arranged to deliver against the work piece a series of impulses directed away from said feed member, and means for imparting such impulses to said operating tool, said oscillating means and said impulse-imparting means being synchronized to cause each impulse to be delivered against the work piece during each back-feed movement of said feed member, thereby minimizing any tendency of the feed member to exert a back-feed action upon the work piece.

13. A channel opening machine comprising a gage against which a sole having a channel formed therein is held by hand, means for oscillating said gage in the line of feed, a tool constructed and arranged to effect a turning operation upon the channel lip by delivering thereagainst a series of impulses transverse to the line of feed and directed away from said gage, and means for imparting such impulses to said lip-turning tool, said oscillating means and said impulse-imparting means being synchronized to cause each impulse to be delivered against the work piece during each back-feed movement of said gage, thereby minimizing any tendency of the gage to exert a back-feed action upon the sole.

14. A channel opening machine comprising a blade-like gage adapted to enter a channel formed in the sole of a shoe and to position the sole by engagement with the shoulder of the channel, means for oscillating said gage in the line of feed, a tool for raising the channel lip, and means for reciprocating said lip-raising tool in a path substantially transverse to the line of feed and parallel to said gage, said oscillating means and said reciprocating means being synchronized to cause said lip-raising tool to deliver each of its impulses against the lip during the back-feed stroke of said gage, thereby minimizing any tendency of the gage to exert a back-feed action upon the sole.

CHARLES G. BROSTROM.
